RETRACTABLE FIRE ESCAPE

John Schultz, Rolland E. McCrillis, and Walter C. Coaty, Marshfield, Wis.

Application April 8, 1939, Serial No. 266,830

8 Claims. (Cl. 228—42)

This invention relates to the class of fire escapes and pertains particularly to an improved retractable fire escape structure.

The present invention has for its primary object to provide a fire escape which is designed primarily for use upon small buildings such as residences, boarding houses or small hotels, wherein an escape ladder is maintained in wound up condition in a suitable compartment in a wall of the building above the highest floor thereof and is releasable to be projected outwardly and downwardly so as to be easily accessible from windows in the building.

Another object of the invention is to provide in an escape structure of the above described character, a novel means for supporting the wound up escape ladder so that when released it will move by gravity outwardly and downwardly to a position spaced from the building wall and will then drop automatically in parallel relation with the wall where it may be easily reached from adjacent windows but will be sufficiently far out to avoid being damaged by a blaze coming from any of the building windows.

Another object of the invention is to provide a novel means for effecting the re-winding of a fire escape ladder of the above described construction, after the ladder has been released for use.

Other objects and advantages of the invention will become apparent as the description of the invention proceeds and the invention will be best understood from a consideration of the following detailed description taken in connection with the accompanying drawing forming part of this specification, with the understanding, however, that the invention is not to be confined to any strict conformity with the showing of the drawing but may be changed or modified so long as such changes or modifications mark no material departure from the salient features of the invention as expressed in the appended claims.

In the drawing:

Fig. 1 is a view illustrating diagrammatically the application of the present invention to a building wall, the invention being seen from the outside of the building.

Figure 2 is a vertical sectional view through the fire escape showing the same in extended position.

Fig. 3 is a view in top plan of the ladder drum and latching means, the ladder being moved from the drum.

Fig. 4 is a sectional view taken substantially on the line 4—4 of Fig. 3.

Fig. 5 is a view illustrating schematically the

lower portion of the ladder with the closure and the spring connecting means therebetween.

Referring now more particularly to the drawing, the numeral 1 designates a portion of a wall of a building in association with which the present escape structure is to be employed. In accordance with the present invention, there is provided in the wall 1, above the top floor and in line with a vertical series of windows of the several underlying floors, an opening 2 in which is secured a housing 3. The outer side of this housing is located flush with the outer side of the wall 1 and is provided with a closure 4 which is unsecured and is frictionally held in place so that the ladder carrying structure within the housing 3, when released and moved outwardly by gravity, will force the closure to open position, the door being attached to the ladder for the purpose hereinafter described.

Within the housing at each side thereof there is secured in outwardly and downwardly inclined position a set of stationary tracks, which is indicated generally by the numeral 5, each set being made up of the two track bars or rails 6 which are arranged in spaced parallel relation as shown, the forward ends of the rails terminating in the plane of the opening of the casing, as shown.

Mounted between the rails 6 of each set of tracks is a set of sliding tracks indicated generally by the numeral 7 and consisting of the two spaced bars 8, each of which is in slidable engagement with the inner face of a rail 6, as shown. These bars are held in spaced relation in any suitable manner as by the provision of the transverse end spacing members 9. Each set of sliding tracks is designed to slide forwardly and downwardly on a stationary set of tracks to project a substantial distance outwardly from the casing 3 and the outward movement of the sliding tracks is limited by suitable stop members 10 engaging the fixed stops 11 on the adjacent rails 6.

Mounted between the bars 8 of each set of sliding tracks is a wheel 12 having a central rotatable bearing unit 13 in which is secured the axle 14 of a drum 15. This drum comprises a cylinder portion 16 having a single flange 17 at one end and two spaced flanges 18 at the opposite end between which spaced flanges a short cylinder portion 19 is located, thus providing a main winding cylinder and an auxiliary winding cylinder.

Attached to the main cylinder 16 of the drum is one end of a ladder 20 which is made up of flexible side strands 21 and cross members or rounds 22. The side strands 21 of the ladder are attached at their outer or lower ends to the inner

face of the door 4 and function to hold the door closed as hereinafter more specifically described. Attached to the auxiliary drum cylinder 19 is one end of a chain or small cable 24 which passes through suitable channels or conduits and over suitable pulleys 25 from the casing 3 into the adjacent wall 1. This cable or chain extends downwardly in the building wall to the bottom of the building and is accessible from within a room of the building through a suitable opening 26, for the purpose hereinafter described. Disposed within the casing 3 and extending transversely of the same is a rock shaft 27, the ends of which may be suitably supported as in bearings 28 which are here shown as being carried by or mounted upon the top fixed rails 6. Adjacent each end of the shaft 27 is a latching finger 29 which extends forwardly and these fingers are spaced apart so that the drum unit 15 when it is retracted into the housing or casing 3, may position between them. The fingers will then be located adjacent the outer sides of the end flanges 17 and 18 of the drum. Each of the drum flanges 17 and 18 has secured to its outer face the annular series of teeth or pins 30 and when the drum is retracted into the casing, these teeth will be brought into position where one may be engaged by the hook of a latch finger 29 so as to hold the drum in the casing. A suitable spring 31 is connected with each latch finger to normally urge the same downwardly, the downward rocking movement of the finger being limited in any suitable manner as by the provision of a stop member 32 which might be connected with a rock shaft 27 to engage a finger 33 carried by a fixed part of the mechanism such as the track 6. Thus when the latch fingers are out of engagement with the pins 30, these stop members 32-33 will cooperate to hold the fingers in the proper position where, when the ladder drum is retracted into the casing, the pins 30 will ride under the fingers to be engaged thereby.

At the central part of the rock shaft 27 a lever arm 34 is secured to the outer end of which is attached a pull cord or cable 35. This cable extends from the casing over suitable pulleys 36, downwardly through the wall of the building and in passing through the wall it lies adjacent to doors or openings 37 which are accessible from within the adjacent rooms of the building so that in the event of fire, an occupant of any of the rooms which are adjacent the fire escape, may reach the cable or chain 35 through a door opening 37 and by pulling on the chain lift the fingers 29 for the release of the ladder drum.

When the escape structure is not in use, the sliding track units 7 will be retracted into the casing 3 between the bars of the track units 5 and the ladder carrying drum will be shifted from the position in which it is shown in Fig. 1 of the drawing to the opposite end of the tracks as is illustrated in dotted outline in this figure. The ladder will be wound up on the drum and the door 4 will be in position in the front end of the casing where it is held by the wound up ladder. The fingers 29 hold the drum against turning and also prevent the forward sliding movement of the shiftable or sliding tracks.

When the fingers 29 are raised, the ladder carrying drum as well as the sliding tracks will tend to move forwardly in the casing due to the inclined position of the tracks and this will allow the casing door 4 to fall out. The door will then function as a weight means to effect rotation of the drum and the unwinding of the ladder. The

sliding tracks will move outwardly until checked by the stops 10-11 and the drum will also roll upon its wheels 12 to the forward ends of the sliding tracks or to the position in which it is shown in full lines in Fig. 1. In order that the extended ends of the sliding tracks may be firmly held and prevented from sagging, there may be attached to their forward ends suspension cables 38, the other ends of which may be firmly anchored in the building wall.

When the ladder drum is in retracted position in the casing 3, the chain or cable 24 will be unwound from the auxiliary drum 19 but as the ladder drum turns for the unwinding of the ladder, this cable 24 will be wound up on the auxiliary drum. By means of this cable 24, the retraction of the ladder drum and the re-winding of the ladder thereon may be effected, access being had to this re-winding cable through the doors 26 in the building wall.

In order to accelerate the initial movement of the cable drum 15 and the sliding tracks 7, the lower end of the ladder 21 may be coupled with the door 4 by a pair of springs 39 which will be stretched or placed under tension when the drum and sliding tracks are retracted into the casing 3 and the door 4 is in position in the casing opening. It will be readily seen that when these springs are stretched after the parts have been housed in the casing, they will react when the holding fingers or pawls 29 are raised to release the ladder drum, so as to give a forward jerk to the drum, thus causing it to move rapidly forwardly and strike the inner side of the door 4 with sufficient force to insure it being knocked out so that the drum and sliding tracks may be projected from the casing.

From the foregoing, it will be readily apparent that there has here been disclosed a novel fire escape mechanism which is a relatively simple construction and, therefore, may be economically included in a building as the same is under construction or might be installed at small expense in a wall of a completed building, and it will also be readily apparent that this device will function efficiently and will not be likely to fail at a crucial moment due to complexity of construction.

What is claimed is:

1. A fire escape structure for buildings, comprising a pair of fixed track units disposed in spaced parallel relation and at an inclination within and transversely of a building wall and directed toward an opening therein, a rotatably mounted drum, means supporting said drum between said track units whereby said drum may move outwardly and downwardly from within the wall through said opening to a position before one face thereof, means releasably holding the drum against outward movement, a flexible ladder adapted to be wound up on said drum, means forming a closure for said opening for effecting the turning of said drum and the unwinding of the ladder therefrom when the drum has moved to the said position forwardly of the wall, and means connected with the closure for starting the outward movement of the drum when the holding means is released.

2. A fire escape for buildings, comprising a casing adapted to be mounted within a building wall and having an open side directed outwardly with respect to the wall, a pair of fixed track units disposed in outwardly and downwardly inclined position within the casing, a drum, means supporting said drum upon said track units whereby the drum may have rotary movement

and may move longitudinally of said tracks for extension through the open side of said casing to a position forwardly of said wall, a flexible ladder wound upon said drum, releasable means for maintaining the drum within the casing with said ladder wound thereon, a closure for the open front of said casing, and spring means connecting an end of the ladder with said closure, the closure functioning as a weight means for effecting the 10 unwinding of the ladder from the drum when the drum is projected outwardly from the casing, and said spring means being under tension when the drum is in the casing and functioning to start the projection of the drum outwardly.

15 3. A fire escape for buildings, comprising a pair of fixed track units secured in spaced parallel relation in an opening in the building wall, said track units having an outward and downward inclination, a closure member for the outer side 20 of said opening, a movable track unit slidably mounted upon each of the first units for extension from said opening outwardly from the building wall, a drum, means rotatably supporting the drum at its ends between said movable track units, 25 said means facilitating the shifting of the drum longitudinally of the track units, a flexible cable ladder having one end secured to the drum to be wound up thereon, the other end of said ladder being connected to said closure member, means 30 releasable from a point remote from said wall opening for retaining said drum and movable track units in retracted position within the wall opening, and means for effecting the retraction of said drum and slideable track units into the wall 35 opening and winding up said ladder on the drum from a point remote from the wall opening.

4. A fire escape structure for buildings, comprising a casing mounted within a wall of the building and having an outwardly directed open 40 side, a pair of track units fixed within the casing and disposed at a downward and outward inclination, a pair of movable track units each carried by a fixed unit for limited longitudinal movement thereon, each of said movable units comprising a pair of spaced parallel bars, a wheel mounted between each pair of bars, a drum disposed between said wheels and rotatably connected therewith, a flexible ladder having one end secured to said drum to be wound up thereon, 45 a removable closure for the open side of said casing having the other end of said ladder attached to the inner side thereof, an annular series of teeth carried upon one end of the drum concentrically therewith, oscillatable latch means 50 within the casing for engagement with said teeth to retain the drum and sliding track units retracted in the casing, and means for shifting said latch finger from a point remote from the casing to effect the release of the drum.

5. A fire escape structure for buildings, comprising a casing mounted within a wall of the building and having an outwardly directed open side, a pair of track units fixed within the casing and disposed at a downward and outward inclination, a pair of movable track units each carried by a fixed unit for limited longitudinal movement thereon, each of said movable units comprising a pair of spaced parallel bars, a wheel mounted between each pair of bars, a drum disposed between said wheels and rotatably connected therewith, a flexible ladder having one end secured to said drum to be wound up thereon, 55 a removable closure for the open side of said casing having the other end of said ladder attached to the inner side thereof, an annular series of teeth carried upon one end of the drum concentrically therewith, oscillatable latch means within the 60 casing for engagement with said teeth to retain the drum and sliding track units retracted in the casing, means for shifting said latch finger from a point remote from the casing to effect the release of the drum, and spring members forming 65 a part of said ladder at the end adjacent the closure and adapted to be placed under tension when the ladder is wound up on the drum and retracted with the movable units into the casing and the closure is disposed in the open side of the 70 casing.

series of teeth carried upon one end of the drum concentrically therewith, oscillatable latch means within the casing for engagement with said teeth to retain the drum and sliding track units retracted in the casing, means for shifting said 5 latch finger from a point remote from the casing to effect the release of the drum, an auxiliary drum forming a part of said first drum and concentric therewith, and a cable connected at one end with the auxiliary drum and unwound therefrom when the said drums are retracted into the casing, said cable being wound up upon the auxiliary drum when the first drum is rotated for the unwinding of the ladder whereby its reverse rotation may be effected by pulling the cable from a 10 point remote from the casing.

6. A fire escape structure for buildings, comprising a casing mounted within a wall of the building and having an outwardly directed open side, a pair of track units fixed within the casing 20 and disposed at a downward and outward inclination, a pair of movable track units each carried by a fixed unit for limited longitudinal movement thereon, each of said movable units comprising a pair of spaced parallel bars, a wheel 25 mounted between each pair of bars, a drum disposed between said wheels and rotatably connected therewith, a flexible ladder having one end secured to said drum to be wound up thereon, a removable closure for the open side of said casing 30 having the other end of said ladder attached to the inner side thereof, an annular series of teeth carried upon one end of the drum concentrically therewith, oscillatable latch means within the casing for engagement with said teeth to 35 retain the drum and sliding track units retracted in the casing, means for shifting said latch finger from a point remote from the casing to effect the release of the drum, and means for accelerating the initial forward movement of the 40 drum in the casing when said latch means is disengaged from the drum teeth.

7. A fire escape structure for buildings, comprising a casing mounted within a wall of the building and having an outwardly directed open 45 side, a pair of track units fixed within the casing and disposed at a downward and outward inclination, a pair of movable track units each carried by a fixed unit for limited longitudinal movement thereon, each of said movable units comprising a pair of spaced parallel bars, a wheel mounted between each pair of bars, a drum disposed between said wheels and rotatably connected therewith, a flexible ladder having one end secured to said drum to be wound up thereon, a 50 removable closure for the open side of said casing having the other end of said ladder attached to the inner side thereof, an annular series of teeth carried upon one end of the drum concentrically therewith, oscillatable latch means within the 55 casing for engagement with said teeth to retain the drum and sliding track units retracted in the casing, means for shifting said latch finger from a point remote from the casing to effect the release of the drum, and spring members forming 60 a part of said ladder at the end adjacent the closure and adapted to be placed under tension when the ladder is wound up on the drum and retracted with the movable units into the casing and the closure is disposed in the open side of the 65 casing.

8. A fire escape structure for buildings, comprising a pair of fixed track units disposed in spaced parallel relation and at an inclination within and transversely of a building wall and 75

directed toward an opening therein, a rotatably mounted drum, means supporting said drum between said track units whereby said drum may move outwardly and downwardly from within the wall through said opening to a position before one face thereof, means releasably holding the drum against outward movement, a flexible ladder adapted to be wound up on said drum, means forming a closure for said opening for effecting the turning of said drum and the unwinding of the ladder therefrom when the drum has moved

to the said position forwardly of the wall, and means connected with the closure for starting the outward movement of the drum when the holding means is released, and means operable from within the building for retracting the drum and simultaneously reversely turning the drum to re-wind the ladder thereon.
